UNITED STATES PATENT OFFICE.

GEORGE J. NETH, OF DAYTON, OHIO.

AUTOMATICALLY-CONTROLLED PAPER CUTTER.

Application filed November 27, 1922. Serial No. 603,473.

To all whom it may concern:

Be it known that I, GEORGE J. NETH, a citizen of the United States, residing at Dayton, in the county of Montgomery and State of Ohio, have invented certain new and useful Improvements in Automatically-Controlled Paper Cutters, of which the following is a specification.

This invention relates to automatically-controlled paper-cutters, and has particular reference to the improvements which I have made in the automatically-controlled paper-cutter illustrated and described in my United States Letters Patent No. 1,094,374 granted

April 21, 1914.

It is one of the principal objects of the present invention to enable the operator to readily and firmly grip the paper for the purpose of drawing it to the desired position for cutting. After a sheet of paper has been cut from a roll, it is difficult to pull out another length of it for the reason that its free edge does not project a sufficient distance beyond the edge of the cutter bar to enable it to be firmly gripped by the fingers. My invention, on the other hand, obviates the above difficulty by the provision of means for moving the cutter bar rearwardly a sufficient distance to permit the paper to be firmly gripped and pulled outwardly the extent necessary to enable a strip of the desired length to be cut from the roll after the cutter bar drops to its normal position.

It is another object of the present invention to provide means to prevent the paper from buckling or crumpling when the cutter bar is moved rearwardly to permit the free end of the paper to be firmly gripped.

In the accompanying drawings, Figure 1 is a side elevational view of my automatically-controlled paper-cutter containing the improvements to be hereinafter described. Figure 2 is a front elevational view of one side of the same. Figure 3 is a longitudinal sectional view taken on the line 3-3 of Figure 2, showing the cutting bar and the paper-tensioning roller in their normal positions. And Figure 4 is a partial sectional view taken on the same line of Figure 2, showing the cutting bar and the tensioning roller in their raised positions.

Throughout the specification and drawings similar reference characters denote corresponding parts.

Referring to the accompanying drawings, the numeral 1 designates a base upon each end of which there is mounted a standard 2 which supports one end of a top rail or hand rest 3. Suitably secured between the standards 2, 2 is a spindle or rod 4 upon which there is mounted a roll 5 of paper that is preferably for wrapping purposes.

Pivotedly supported from each standard 2 is an automatic brake-bar 6 which constantly engages the roll 5 to assist in controlling the revolution of said roll and hold the same stationary when not in operation.

Projecting from each standard 2 is a side arm 8 which is preferably connected thereto by means of its short extensions 9 which are securely clenched over said standard as shown in Figure 1. Said arms are each formed with a slot 10 in its outer end.

The free end 11 of the paper from the roll 5 passes over an idle roller 12, the ends of which are journaled in the side arms 8; and thence down and under a rod 13 against which it is maintained by a tension-bar 14 fast on a shaft 15 which is also journaled in the side arms 8. One end of the shaft 15 projects some distance beyond one of said side arms to receive a short arm 16 carrying a weight 17 by means of which said tension bar is automatically operated. This tension-bar 14 locks the paper between it and the rod 13 until the paper is pulled outwardly by the operator, whereupon said weight, being of the proper heft, will permit the tension-bar to move sufficiently to permit the paper to pass it. Said paper after passing between the rod 13 and tension-bar 14, as just described, extends downwardly, passing through a longitudinal slot 18 in a cutting bar 19, terminating just a short distance beyond it, as shown in Figures 3 and 4.

Projecting from the ends of the cutting bar 19, which is preferably constructed of a good grade of steel, are guiding pins 20 which are freely slidable in the slots 10 of the side arms 8. The cutter bar 19 is turned or bent to project rearwardly from its slot 18, in the direction of the slots 10, and is then bent downwardly at right angles to the latter to provide a plate portion 21 for a purpose to be hereinafter described. The cutter bar 19 is secured at each end to the upper end of a hinge 22 formed at its lower end with a sleeve 23 through which passes a shaft or rod 24 journaled in the side arms 8. These hinges 22 pivotally sup-

port the cutter bar 19 for an up and down movement.

After a strip of paper has been severed from the roll 5 along the cutting edge of the bar 19 as shown in Figure 3, and it is desired to grip the paper to pull out another length of it, the pressure of the fingers should be exerted against the plate portion 21 of the cutter bar 19 to raise it to the position shown in Figure 4. When the cutter bar has been moved to this position, it will leave exposed a sufficient length of the free end 11 of the paper to be readily grasped by the fingers and drawn outwardly the desired distance for being cut by the bar 19 which will drop downwardly to its normal position when the paper is drawn outwardly. It is thus possible with my improved means to readily grasp the free end of the paper and pull it outwardly the desired distance each time the paper is to be cut.

For the purpose of preventing the paper from buckling when the cutter bar is pushed inwardly by its plate portion 21, the following means are provided. Pivottally secured to each end of the idle roller 12, between the side arms 8, is an arm 25 which is arched at its rear end to rest upon the rod 13 when in its lowermost position. These arms 25, which project forwardly and then upwardly from their arched portions, have journaled between their upturned ends a tension roller 26 beneath and in engagement with which the paper passes. Now, when the cutter bar is moved rearwardly by the pressure exerted against its plate portion 21, the tension roller 26 will prevent the paper from bulging outwardly between the cutter bar and the rod 13. As the cutter bar moves inwardly, its upper end 27 will engage the arms 25 in time to raise them and the tension roller 26 which they carry, a sufficient distance to permit the cutter bar to move under the roller. By the time the cutter bar starts to engage the arms 25, it will have moved over the paper a sufficient distance to prevent it from buckling. Then,

when the cutter bar drops downwardly to its normal position after a firm grip has been secured upon the paper, the tension roller 26 will be permitted to descend to its normal position over the latter.

I do not wish to be limited to the details of construction and arrangement herein shown and described, and any changes or modifications may be made therein within the scope of the subjoined claims.

Having described my invention, I claim:

1. In a paper cutter, the combination with standards provided with side arms, of paper-tensioning means secured between the side arms, a cutter bar movable between said side arms toward and away from the tensioning means, arms pivotally secured to the interior portions of the side arms, and a rod secured between the pivotal arms over the paper between the tensioning means and the cutter bar, to prevent the paper from buckling when the cutter bar is moved rearwardly.

2. In a paper cutter, the combination with standards provided with side arms, of paper-tensioning means secured between the side arms, a cutter bar movable between said side arms toward and away from the tensioning means, arms pivotally secured at their rear ends to the interior portions of the side arms and having upturned front ends, a rod secured between the front ends of the pivotal arms over the paper between the tensioning means and the cutter bar, to prevent the paper from buckling when the cutter bar is moved rearwardly, and an upwardly projecting part on the cutter bar adapted to engage the upturned ends of the pivotal arms, in time to raise them a sufficient distance to permit the cutter bar to move beneath the rod which they carry.

In testimony whereof I have hereunto set my hand this 25th day of November, 1922.

GEORGE J. NETH.

Witness:

HOWARD S. SMITH.
